TRANSPOSABLE WINDOW FAN ASSEMBLY

Jacob Walter Kisling, St. Louis County, Mo.

Application March 10, 1950, Serial No. 148,953

9 Claims. (Cl. 98—94)

1

This invention relates to transposable window fan assemblies, and more particularly to a window fan which is susceptible of physical reversal of its inlet-outlet position with respect to a window in which it is installed.

This applicant is aware that certain provisions have heretofore been made to enable physical reversal of a motor driven fan assembly from an inside-discharge to an outside-discharge relation to the window in which it is installed. However, all such provisions as have heretofore come to the attention of this applicant, are characterized by complicated and expensive supporting provisions, or in the case of certain structures require the fan-motor assembly to be manually lifted, reversed and reset in the altered relation to the window. Other shortcomings and difficulties have characterized the various assemblies for this purpose, thus far offered to the trade. It is accordingly a major and general objective of the present improvements, to render virtually effortless the physical transposition of the fan assembly as between out-draft and in-draft window relations.

The present invention may be summarized by reference to the preferred embodiment thereof as produced for the trade, as including a window panel preferably of a width-adjustable character so as to adapt it to different window openings, together with a supporting frame in or on which is carried a motor and fan assembly together with a pair of frame-supporting arms located at diametrically opposite zones near a panel opening. One of such arms and the supporting frame, are provided with a pivotal connection adequate to support the frame and contents both when in operative or normal position with respect to the panel, and also when the frame and fan are conditioned for movement between an in-draft relation and an out-draft relation of the fan. The companion supporting arm for the frame on or in which is mounted the motor and fan, is provided with a detachable clamp connection including positively interfitting elements which position the frame in proper spacing from the panel and likewise position the frame, after transposition, against rotation about an axis connecting the supporting arms.

A further important object of the invention is realized in an improved cushioned pivotal connection between one margin of the frame and a supporting arm carried by the panel.

A still further and important objective is realized in an improved design of clamp formed of detachable elements for selectively yet posi-

2

tively interconnecting the frame supporting the fan and motor, with an arm which is fixed to the panel.

An improved supporting and connecting structure objectively enables the fan, motor, frame and related parts to be moved through an angular range of 180 degrees, about an axis normally connecting two frame supports, while the frame and contents remain supported on at least one of such supporting elements, thus rendering relatively effortless the act of transposition.

The foregoing and numerous other objects and advantages will more clearly appear from the following detailed description of a presently preferred embodiment of the invention, particularly when considered in connection with the accompanying drawing, in which:

Fig. 1 is a face view of a transposable window fan assembly embodying the present improvements, as viewed from the inside or room side thereof;

Fig. 2 is a fragmentary sectional elevation taken in a vertical plane medially, and extending depthwise of the fan and motor assembly, and showing a portion of a frame structure for supporting same, Fig. 2 being particularly located by line 2—2 of Fig. 1;

Fig. 3 is a fragmentary top plan view showing certain features of the detachable clamp assembly shown at the upper portion of the panel and motor supporting frame, Fig. 3 being located by line 3—3 of Fig. 2;

Fig. 4 is a fragmentary sectional view of the detachable clamp assembly shown at the upper portion of the panel and the fan-motor frame, Fig. 4 being particularly located by line 4—4 of Fig. 2, and

Fig. 5 is a substantially enlarged, vertical sectional view through a lower connection between the fan and motor supporting frame, and a lower supporting arm therefor, Fig. 5 illustrating a special form of ball and socket structure, and being located by line 5—5 of Fig. 1.

Referring now by characters of reference to the drawing, and first to Fig. 1, there is shown an adjustable-width window panel generally indicated at 10, and including a central plate element 11, together with laterally adjustable wings 12 at the left and 13 at the right hand side. Provision for adjustment of the wings between relatively extended or retracted positions may be of any suitable nature, but is shown as comprising a pair of horizontal threaded studs 14 carried by plate element 11, each of these studs operating, incident to adjustment, along horizontal slots 15.

in each of the wings 12 and 13, and the adjusted position of the studs, hence of the wings, maintained by wing nuts 16. The top and bottom margins of the panel body 11 are provided as appears in Fig. 2, with channel flanges 17 and the wings 12 and 13 provided with interfitting flange portions 18 so that the wings are smoothly guided incident to width adjustment, through the coaction of the marginal channels and flanges 17, 18.

The central part of the body portion 11 of the panel is provided with a circular opening 20 providing for ingress or egress of air, according to the adjusted setting of the fan assembly. The opening 20 as will be noted, is substantially in register with the propeller fan P which is driven by a motor M, and the motor and fan suitably supported in a frame characterized by a guard or grille G which overlies the opposite sides and the margins of the fan and motor assembly for the usual purposes of protection. Extending peripherally and substantially in a plane which is midway of the depth of the supporting frame and guard assembly, is a heavy metal annulus 21, through which connections are made at diametrically opposite zones outside of the air opening 20, to a pair of frame supporting arms. One such arm projects horizontally and inwardly from an upper portion of the body 11 of the panel and is generally designated at 22, a similar such arm but which is relatively inverted, being shown in the lower region of the panel body 11 and generally indicated at 23.

The frame within which is supported the motor and fan, is by preference and as shown, formed substantially symmetrically with respect to a vertical plane parallel to but spaced inwardly of the panel member 11. The frame is likewise substantially symmetrical with respect to a depthwise vertical plane at a right angle to the member 11, such planes of symmetry intersecting in a vertical line drawn between the upper and lower frame supporting connections later herein described.

It is a preference to provide for a yieldably opposed lifting actuation particularly of the supporting arm 22, but by further preference of the arm 23. To this end, a right angular flange 25 is formed as a part of the arm 22, and a similar, but depending flange 26, on the arm 23. Each of the flanges 25—26 is provided slightly inwardly of its ends with suitable bolt apertures one of which is indicated at 27 for the reception of mounting bolts 30. A pair of resilient washers formed of a rubber or other high resilient stock are indicated at 31. These may, as is preferred, be bonded to metal washers 32 also threaded over the mounting bolts 30, one such resilient bolted assembly being provided in each of the locations identified at 30 in Fig. 1.

Referring now to the improved provisions for directly supporting and facilitating transposition of the fan, the lowermost such assembly, best shown by Fig. 1 as to location, and by Fig. 5 as to detail, includes a two-part screw clamp, the principal elements of which are indicated at 35, below the supporting arm 23, and 36 immediately thereabove. Threaded into the element 36 is a screw 37 formed integrally with the member 35 and extending through an aperture 40 in the arm member 23, thence threaded into a tapped axial bore in the member 36.

Since in some installations the lower part of this connection may rest on a window sill or other plate element, there is provided a resilient pad which may be a rubber annulus 41 secured to the

lower clamp element 35 as by a single assembly screw extending upwardly into a tapped recess in member 35.

The upper member 36 of the two major parts of the clamp, is initially counterbored to provide a socket 42, in the lower portion of which is a coil compression spring 43 bearing against a ball 44 forming one of the elements of a swivel joint, the upper margin 45 of the element 36 being peened or otherwise deformed inwardly so as, with the socket 42, to embrace the ball 44, thus constituting the ball and socket joint as a part of the connection comprised of elements 35, 36, 44 and connected parts.

A threaded stud 44' extends upwardly of ball 44 and is provided with a nut 46, the stud extending through an aperture 47 in the outer frame element 21 of the fan supporting frame.

It will now appear that the elements just described constitute an effective swivel or pivotal connection, as well as a lower anchorage or hold-down assembly which, in the example shown, is located at the bottom of the fan and below the motor, frame and guard structure, and in a position such that the axis of the assembled elements 35—36, constitutes a prolongation of a vertical axis midway of the depth of the frame unit, for reasons which will hereinafter be made obvious.

Directly opposite the lower connection just described, is a detachable upper connection, coacting with the upper supporting arm 22 which in effect constitutes a part of such connection, as will now be detailed:

From reference to Figs. 2, 3 and 4 it will be seen that the peripheral ring 21 is provided with a radially projecting, threaded stud 50, the stud being headed at 51, below the ring 21. The stud 50 threadedly receives a large milled clamp nut 52, overlying the supporting arm 22. Projecting outwardly of the ring 21 at opposite sides of the axis heretofore identified, and which is coincident with that of the stud 50, are a pair of lugs 53 and 54 on opposite sides of the vertical median axis above described. The lugs 53 and 54 are by preference, and as will be apparent from Fig. 3, of rectangular section, and are closely and detachably received in interlocking relation in apertures 55 or equivalent sockets equally spaced at the sides of the stud 50, and each accommodating one of the lugs. It is noted as sufficient if only one lug such as 54 be provided, with a pair of apertures or sockets 55 equally spaced and offset from the axis of transposition, each aperture or socket accommodating the lug 54 in one of the operative positions of the fan supporting frame. The free end of the supporting arm 22 is characterized by an open slot 56, which is of a width to receive the stud 50 when the clamp screw 52 is partly or completely unthreaded therefrom. Attention has heretofore been directed to the fact that the arm 22, by virtue of the resilient mounting thereof is susceptible of lifting and lowering movement, toward and away from the fan-motor supporting frame. This provision alone and more particularly in cooperation with the similar flexible mounting of the arm 23, enables, with the nut 52 released, a lifting of the upper arm and a depression of the lower arm such that the lugs 53 and 54 may readily be backed out of the sockets therefor in the adjacent supporting arm. The resilience of the arms afforded by the elastic mounting thereof, similarly effects an instant interfitting relation of the lugs in the apertures therefor, when the fan supporting frame is brought to its operative position,

irrespective of transposition. The resilience of the upper arm 22 and the elastic elements 31, in coaction with the nut 52 and bolt 51, serves desirably to keep the frame under tension, with minimization of vibration and noise. It is noted that this is possible by reason of the holdown effect of the ball 44 and socket 42.

The manner of manipulation of the frame and contents incident to transposition is thought to have been rendered fully apparent from the foregoing description of structure, but it may be noted for completeness that, assuming it is desired to change the direction of air current between inflow and outflow relations, the nut 52 is backed off of stud 50. It is not usually necessary fully to remove the nut, but merely to back same away sufficiently to permit disengagement of the lugs 53, 54 from their sockets. As soon as this is done, the nut 52 is grasped and drawn inwardly toward the room side of the assembly, the frame, together with fan and motor therein, rotated about the vertical medial axis described, as is permitted by the swivel action of the ball and socket joint below the frame. During transposition, the spring 43 serves as a resilient support for the operative elements and frame, generally indicated at F. Such bodily movement of the fan assembly through 180 degrees, will, now obviously, effect a full reversal of direction of air flow. Upon completion of the half turn required for the transposition, the stud 50 is again inserted in the slot 56, being limited in such inward movement by the inner end of the slot, whereupon the lugs 53, 54 are in exact register with the conforming apertures therefor. The nut 52 may now be threaded up on the stud 50 so as to bring the lugs fully into their sockets, and the nut and stud now acting firmly to clamp together the supporting ring 21 and the supporting arm 22. The fan is now restored to operative condition to deliver air in the desired direction either into or out of the room, as the case may be. Such position is fixed by the upper and lower connections as described, and with the fan circle of the fan P in at least substantial register with the air opening 28 of the panel.

Initial adjustment of the assembly to the width of the window opening will consist merely of backing off the wing nut 16 carried by each of the threaded studs 14, and expanding or retracting the wings 12, 13 preferably equally, so that the side marginal flanges thereof, will snugly fit the stiles or other vertical framing elements of the window, following which the wing nuts are firmly threaded up.

Although the invention has been described by particularized reference to a single preferred embodiment, the detail of disclosure should be understood solely as illustrative, and not in any restrictive sense, many variants being possible within the scope of the claims hereunto appended.

I claim as my invention:

1. In a window fan of a physically reversible character, a vertical panel for insertion in a window opening, a motor and a fan operatively connected to the motor, a frame supporting the motor and fan, the panel having an air opening in substantial register with the fan, a top arm element carried by the panel, an arm-engaging element carried by said frame, one of said elements being provided with a lug, the other element including spaced sockets conformed to and adapted to receive said lug in detachable interlocking relation, the lug and lug-conforming sockets being laterally offset from an axis of

transportation of the frame, means for detachably retaining the lug in the socket, a second arm element on a side of the frame opposite the first said arm element, and a swivel connection between the last said arm element and the frame.

2. In a window fan of such character that its inlet and discharge may be reversed in relation to the window, a window panel, a motor, a fan driven by the motor, a substantially circular frame and housing structure for the fan and motor, the window panel having a circular air opening of a diameter not substantially in excess of that of the fan, a pair of supporting arms yieldably attached to the panel in zones diametrically opposite the air opening in the panel, a swivel supporting connection between one of said arms and said frame, the other of said arms being provided with spaced lug-receiving sockets, the frame provided with a lug formed closely to interfit said sockets, and a screw clamp constituting a detachable connection between the frame and the socketed arm, the screw clamp being located substantially on a produced diameter of the frame, and the lug and sockets being laterally offset from said produced diameter, whereby to resist rotation of the frame about an axis normal to that of the fan.

3. In a window fan of a character such as to be transposable by half rotation of the fan assembly about a median axis, a window panel, a motor, a fan driven by the motor, a frame for the motor and fan, the panel having an air opening substantially in register with the fan, a pair of normally horizontal supporting arms carried by the panel in zones diametrically opposite the panel opening, a releasable clamping device carried by one of said arms and detachably connecting same to the frame, separable clamping elements detachably secured to the other said arm, a threaded connection between said elements, the one of said elements nearest the frame, being formed to provide a part-spherical socket, a ball coacting with the socket to constitute swivel connection, a threaded stud on said ball, a nut coacting with said threaded stud for detachably securing same to the frame, and a spring in said socket, adapted to compensate for lost-motion between the socket and ball and further serving with the ball as a yieldable rest element for the frame, when said releasable clamping device is disengaged.

4. In a transposable window fan, a motor, a fan driven thereby, a substantially circular frame supporting the motor and the fan, a window panel having an air opening therein in substantial register with the fan, supporting arms carried by the panel and extended inwardly or toward the room side of the panel, a pivotal connection between one of said arms and the frame, the frame provided near the other said arm with a pair of spaced upstanding lugs, the last said arm being provided with apertures conformed to and adapted to receive said lugs, and a screw clamp including a threaded stud extended radially of the frame, the adjacent lug-receiving arm being apertured to receive said stud, and a clamp screw detachably engaging said stud on the opposite side of the adjacent supporting arm, said arm being adapted for flexing movement toward and away from the frame to a degree such that when the clamp screw is released, the arm and frame may be separated to release the lugs from the lug apertures, whereupon the frame is movable about the opposite or pivotal connection

incident to physical transposition thereof in respect to the panel.

5. The combination and arrangement of elements as recited by claim 4, but further characterized in that the frame is substantially symmetrically formed with respect to a vertical plane, and said clamp screw and said pivotal connection are located substantially in said plane of symmetry.

6. In a window fan of a character such as to be transposable by half rotation of the fan assembly about a median axis, a window panel, a motor, a fan driven by the motor, a frame for the motor and fan, the panel having an air opening substantially in register with the fan, a pair of normally horizontal supporting arms carried by the panel in zones diametrically opposite the panel opening, the frame being provided near one of said arms with a pair of spaced projecting lugs, the adjacent arm provided with apertures conformed to and adapted to receive said lugs, a clamp including a threaded stud carried by and extended outwardly of the frame, the adjacent arm being slotted to receive said stud, a clamp screw on said stud, the adjacent arm being yieldably mounted to enable same to be lifted to remove the lugs from the lug apertures, separable clamping elements detachably secured to the other said arm, a threaded connection between said elements, one of said elements nearest the frame, being formed to provide a part-spherical socket, a ball coacting with the socket to constitute a swivel connection, a threaded stud on said ball, a nut coacting with said threaded stud for detachably securing same to the frame, and a spring in said socket, adapted to compensate for lost-motion between the socket and ball and further serving with the ball as a yieldable rest element for the frame, when said releasable clamping device is disengaged.

7. In a window fan of such character that its inlet and discharge may be reversed in relation to the window, a window panel, a motor, a fan driven by the motor, a substantially circular frame and housing structure for the fan and motor, the window panel having a circular air opening of a diameter not substantially in excess of that of the fan, a pair of supporting arms yieldably attached to the panel in zones diametrically opposite the air opening in the panel, a swivel supporting connection between one of said arms and said frame, the other of said arms being provided with a pair of spaced lug-receiving sockets, the frame provided with a pair of spaced lugs formed closely to interfit said sockets, and a screw clamp constituting a detachable connection between the frame and the socketed arm, the screw clamp being located substantially on a produced diameter of the frame, and the lug and sockets being laterally offset from said produced diameter, whereby to resist rotation of the frame about an axis normal to that of the fan, the swivel supporting connection being of a ball-and-socket type adapted to keep the frame captive when the said lugs and sockets are disengaged.

8. In a transposable window fan, a motor, a

fan driven thereby, a frame supporting the motor and fan, a window panel having an air opening therein in substantial register with the fan, supporting arms carried by the panel, a pivotal connection between one of said arms and the frame, the frame provided near the other said arm with an upstanding lug, the last said arm being provided with spaced apertures conformed to and adapted to receive said lug, and a screw clamp including a threaded stud extending radially of the frame, the adjacent lug-receiving arm being apertured to receive said stud, and a clamp screw detachably engaging said stud on the opposite side of the adjacent supporting arm, said arm being adapted for flexing movement toward and away from the frame to a degree such that when the clamp screw is released, the arm and frame may be separated to release the lug from the lug apertures, whereupon the frame is movable about the opposite or pivotal connection incident to physical transposition thereof in respect to the panel.

9. In a transposable window fan, a motor, a fan driven thereby, a substantially circular frame supporting the motor and the fan, a window panel having an air opening therein in substantial register with the fan, supporting arms carried by the panel and extended inwardly or toward the room side of the panel, a pivotal connection between one of said arms and the frame, the frame provided near the other said arm with a pair of spaced upstanding lugs, the last said arm being provided with a pair of spaced apertures conformed to and adapted to receive said lugs, said lugs and said apertures being equally spaced and laterally offset from an axis of transposition of the frame, and a screw clamp including a threaded stud extended radially of the frame, the adjacent lug-receiving arm being apertured to receive said stud, and a clamp screw detachably engaging said stud on the opposite side of the adjacent supporting arm, said arm being adapted for flexing movement toward and away from the frame to a degree such that when the clamp screw is released, the arm and frame may be separated to release the lugs from the lug apertures, whereupon the frame is movable about the opposite or pivotal connection incident to physical transposition thereof in respect to the panel, the pivotal connection being of a ball-and-socket type adapted to keep the frame and therewith the motor and fan, in captive relation to the adjacent supporting arm, when the said lugs and apertures are disengaged.
